UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S WRAP.

SPECIFICATION forming part of Design No. 14,414, dated November 13, 1883.

Application filed August 23, 1883. Term of patent 3½ years.

To all whom it may concern:

Be it known that I, CATHERINE O'HARA, of the city, county, and State of New York, have invented and produced a new and original Design for a Pattern of a Lady's Wrap, numbered 8,815; and I do hereby declare that the engraved prints accompanying this specification convey to any one accustomed to using paper patterns a clear understanding of how a garment made up by the pattern will appear.

The design combines sack-fronts, a half-fitted back with its skirt falling in two box-plaits, a sash-bow ornament in the back below

the waist-line, deep wide sleeves draped up at the lower part of their back edges, and a rolling collar.

What I claim as my invention, and desire to secure by Letters Patent, is—

The design for a lady's wrap, as shown in the engraved prints accompanying this specification.

CATHERINE O'HARA.
